FERDINAND ROSSKOTHEN, OF DRESDEN, GERMANY.

BRAIDING-MACHINE.

1,260,063.

Specification of Letters Patent. Patented Mar. 19, 1918.

Application filed February 16, 1915. Serial No. 3,614.

To all whom it may concern:

Be it known that I, FERDINAND Rosskothen, a subject of the King of Prussia, and resident of Dresden, Lidonienstrasse 5 1, Kingdom of Saxony, German Empire, have invented a new and useful Improvement in Braiding-Machines, of which the following is a specification.

The present invention refers to braiding machines with two sets of bobbins, which are revolving in opposite directions round the braiding point. In this class of machine the threads of one set or group of bobbins are led directly to the braiding 10 point, whereas the threads from the other set or group of bobbins are led, conducted or guided above and below the bobbins and threads of the first group of bobbins and threads, before they reach the braiding 15 point, whereas the threads from the other set or group of bobbins are led, conducted or guided above and below the bobbins and threads of the first group of bobbins and threads, before they reach the braiding point. For convenience of expression, the bobbins and threads of the first group will 20 be called hereafter inner bobbins and inner threads and the bobbins and threads of the second group outer bobbins and outer 25 threads.

There are different systems known for making it possible to lead the threads from the outer bobbins alternately above and below the inner bobbins without interrupting 30 the positive driving of the inner bobbins round the braiding point. Also various methods are known for guiding the outer threads above and below the inner bobbins. Most of these thread guide motions are 35 complicated and not suitable for high speeds and most of these motions are only suitable for one pattern of braid or they require rather complicated alterations, viz. dismounting the machine, changing of cams, 40 etc., when a change of the pattern is required.

The present invention refers to a circular braiding machine with an improved system of guiding the outer threads by simple means 45 above and below the inner bobbins. This system of guiding the thread makes it possible to change easily and quickly the pattern of braid and even makes it possible to alter the pattern of braid, when the machine is 50 running. The new thread guiding arrangement is suitable for the highest speed. This purpose is obtained in the following manner:

The inner bobbins are placed on carriers 55 or shuttles, which are pointed in the direc-

tion of movement or at both ends. The inner bobbin carriers are moved round the braiding point by any of the known systems, which allow unobstructed passage of the outer threads, below the inner bobbin 60 carriers on their way to the braiding point.

The outer bobbins are carried by a frame, which rotates in the opposite direction, but at the same speed as the inner bobbin carriers. The inner bobbin carriers are provided with shields, which are pointed in the direction of movement or at both ends. The threads from the outer bobbins are slipping under or over the smooth rims of these shields. Such shields have been used 65 before in machines of this kind, but the arrangements, which have been used up to now for guiding the outer threads according to necessity above or below these shields were complicated, expensive in their manufacture and to a great extent not suitable 70 for the application of high speeds.

According to the present invention the leading or guiding of the outer threads over and under the points of the shields is performed by applying stationary, (non-revolving) guiding parts (plates, wires or switches), at those places where the outer threads meet with the points of the shields 80 of the inner bobbin carriers.

By altering the shape and position of these guide parts or switches different braiding patterns can be produced and the number of different braiding patterns can still be increased by using these switches in 85 combination with bobbin carriers whose points are movable according to the desired pattern by a curve cut into the path on which the inner bobbin carriers are sliding. By dividing the outer threads into groups, 90 which are guided in paths of different heights, two braids can be produced one over the other. In this case the threads of the one group may be guided by the stationary guide parts or switches and the 95 threads of the other group may be guided by the movable points of the inner bobbin carriers. By arranging the outer threads in groups, which are guided in paths of different heights or elevations, in combination 100 with stationary guides or switches, two or more braids, one over the other, can also be produced by using bobbin carriers, whose points are arranged in different heights. 105 These braids are being braided or inter- 110

meshed with each other by the inner threads. This system of guiding the threads makes it possible to guide two or more outer threads through each of the slots, which are arranged in the path of the inner bobbins for the purpose of allowing the outer threads to pass to the braiding point.

The improved braiding machine is shown in Figures 1-10. Drawings Figs. 1-7 serve to explain diagrammatically the new thread guiding device. Fig. 8 shows an inner bobbin carrier with adjustable points. Fig. 8a shows an arrangement of inner bobbin carriers with movable points governed by a curve. Fig. 9 shows the general arrangement of the machine. The right hand side of the drawing shows a vertical section of the machine and the left hand side an outside view. Fig. 10 shows a perspective view 20 of a part of the machine and thread guiding device.

In the diagrammatical drawings Figs. 1-7 the bobbin carriers $d_1, d_2, \dots$, are shown for convenience of explanation, drawn in a plane. The outer threads $a-a_1$ are shown in section and are represented by a dot. These outer threads move in a circular path, which is shown in the drawing as a straight dotted line $a-a_1$. The outer threads are kept tight, but still elastic, so that they can give way. When the outer thread "a" is moved in the direction a_1 , it moves in a straight path as long as it does not meet with an obstacle. When the thread comes into contact with the polished rims of the shields of the inner bobbin carriers, it is pushed out of the straight path and it slips either over or under the arc shaped shields of the inner bobbin carriers according to its path being arranged above (Fig. 1) or below (Fig. 2) the points of the inner bobbin carriers.

As indicated in the drawings, the thread returns into the original straight path in consequence of its tension after it is no more deflected by the shields. If the path of the outer threads is arranged over the points of the inner bobbin carriers, the outer threads slip over all inner bobbin carriers and move in a line composed of straight and arc-shaped parts, as indicated in the lower part of Fig. 1. If the path of the outer thread is arranged below the points of the inner bobbin carriers, the outer threads move below all inner bobbin carriers and move in a path indicated by the diagram in Fig. 2.

According to the present invention the path of the outer threads is arranged above or below the points of the inner bobbin carriers, and in some of the places, where the outer threads meet with the points of the inner bobbin carriers, stationary guides or switches are arranged, by which the outer threads are led or guided to that side of the inner bobbin carriers, which is opposite

to their ordinary path. This is distinctly shown in the diagrammatical drawings Figs. 3-6.

To the stationary rod f (which in reality is a circular ring), Fig. 3, guide pieces or switches "e" are attached. When an outer thread "a" is moved in the direction $a-a_1$, Fig. 3, it is deflected in the downward direction on those spots, where it comes into contact with the guide pieces or switches e_1, e_2, e_3, e_4 and thereby it is guided below the inner bobbin carriers d_2, d_4, d_6, d_8 . The thread thereby moves in a path, shown in the bottom part of Fig. 3, alternately over one and under one inner bobbin carrier. When giving these guide pieces a symmetrical shape or form, the outer threads are moved in a wave shaped path alternately over and under one inner bobbin carrier as indicated in Fig. 4.

By using different forms and arrangements of the guide pieces, different patterns of braid can be produced. In the arrangement shown in Fig. 5, the outer threads are moved over 2 and under 2 and in the arrangement shown in Fig. 6, over 1 and under 3 inner bobbin carriers.

For convenience of explanation it has been assumed up to now that the bobbin carriers "d" and the switches "e" are both stationary and that the outer threads move in the direction indicated by the arrows; but in reality only the guide pieces or switches are stationary, whereas the inner bobbin carriers move in the opposite direction to the outer threads. By this movement of the outer threads and the inner bobbin carriers in opposite directions, the number of meetings between an outer thread and the inner bobbin carriers is doubled and therefore it is necessary for producing the same kind of pattern of braid, to double also the number of guide pieces and to reduce their length to one half of the sizes shown in Figs. 3-6. As the outer threads and the points of the inner bobbin carriers move at the same speed, but in opposite directions, they always meet at the same spots and although both parts are moving, it is possible to regulate their position as required by the braiding pattern, by stationary nonrevolving guides or switches arranged at the meeting places.

Fig. 7 shows an arrangement, where two sets or groups of inner bobbin carriers are used, whose points are arranged in different heights. The bobbin carriers d_1, d_3, d_5, d_7 have shields with raised points, whereas the bobbin carriers d_2, d_4, d_6, d_8 have shields with lower points, for the purpose of producing double braids. In this case the outer threads are led to the braiding point in two groups. The threads "a" belonging to the one group are moved in a path $a-a_1$ closely above the bobbin carriers d_1, d_3, d_5, d_7 with raised points, whereas the threads belonging to

to the second group are moved in a path $b-b_1$ which is arranged under the raised points of the inner bobbin carriers with raised points, but which is higher or above 5 the lower points of the inner bobbin carriers d_2, d_4, d_6, d_8 .

If the outer threads were not deflected by the guides or switches e_1-e_2 , all the threads "a" of the first group would slip over all 10 inner bobbin carriers, whereas the threads "b" of the other group would slip under the bobbin carriers d_1, d_3, d_5, d_7 and over the bobbin carriers d_2, d_4, d_6, d_8 with lower points. In this manner no braiding action 15 would be performed, but by the action of the guide pieces or switches e_1-e_2 the outer threads are led in some of the meeting places under all the inner bobbin carriers, both under those with high and those with low 20 points, but in those places where the outer threads are not influenced or deflected by the guide parts or switches, they return back to their original path $a-a_1$ or $b-b_1$ respectively.

25 The threads a of the first group therefore perform a movement which is different from the movement performed by the second group of outer threads "b". In the example shown in Fig. 7 the threads a move over 30 2 and under 2 inner bobbins, whereas the threads b of the other group are guided under 3 and over 1 inner bobbin carriers. It will be seen, that therefore the inner threads form with the two groups of outer threads 35 two different kinds of braid which are closely connected or intermeshed by the inner threads. In the finished braid the threads "b" of the lower group are not or very little visible, because they are covered 40 by the threads a of the other group with the inner threads. By arranging the inner bobbin carriers with raised and lowered points in a different manner and also by arranging the guide parts or switches 45 in a different way, different kinds of double braids can be produced. Fig. 8 shows a bobbin carrier with adjustable points, which can be raised or lowered as required. Fig. 8^a shows an arrangement, in which the guiding 50 of the outer threads a under or over the inner bobbin carriers is obtained by providing the inner bobbin carriers with movable points and in which the position of these points is controlled by a curved groove 55 p , which is cut into the path G , in which the inner bobbin carriers are sliding. The inner bobbin carriers d carry with the pivots q the parts s , which are pointed in the direction of movement. On the other end of 60 the parts s , these parts carry by a pivot the tongue r , which slides in the curved groove p of the sliding path G . When these movable points of the inner bobbin carriers meet with an outer thread a , this outer thread 65 will pass over and under this bobbin car-

rier, if the respective point of this bobbin carrier has been moved downward or upward.

By altering the form of the curve for moving the points of the bobbin carriers, 70 different kinds of braid can be produced. The system of guiding the threads by movable points of the inner bobbin carriers is chiefly applicable in such cases, where it is intended to produce several braids at the 75 same time one over the other. In this case the outer threads are divided (similar to the arrangement shown in Fig. 7) in two groups a and b , which are moved along the inner bobbin carriers into paths arranged in different heights. The result is similar as explained with regard to Fig. 7, but the number of braiding patterns can be considerably increased by the simultaneous application 80 of bobbin carriers with stationary and movable points.

In the examples shown in the drawings, it is always assumed, that the guiding parts or switches are arranged above the inner bobbin carriers and that the outer threads 90 are led by the switches below the points of the bobbin carriers. The arrangement can also be reversed and the guiding parts or switches can also be arranged below the inner bobbin carriers. The first arrangement is preferable, because the whole arrangement of the machine is thereby simplified. The guiding parts or switches e can be made of metal sheets or wires and by exchanging these guide parts or switches 100 the pattern of braids can be altered in a very convenient manner.

The general arrangement of the machine is shown in Fig. 9 in which the right hand side shows a vertical section of the machine 105 and the left hand side a front view. The frame A which carries the outer bobbins F and also the frame B, which drives the inner bobbins J round the braiding point C by means of swinging drivers K, or any 110 other suitable means, are carried by a stationary hollow pillar. The frames A and B are revolved by the driving shaft D and bevel wheels E_1, E_2, E_3, E_4, E_5 . Both frames are running at the same speed, but 115 in opposite direction. The threads c from the inner bobbins are running directly to the braiding point C, whereas the threads a from the outer bobbins F are first led to the thread guides o , which are revolving with 120 the frame A and from there over or under the inner bobbin carriers to the braiding point. The inner bobbin carriers d are sliding with slides in an annular or ring shaped path G , which is interrupted by slots L for 125 the purpose of allowing the passage of the outer threads a . The ring f , which carries the guiding parts or switches e is fastened to the frame of the machine, closely above the annular path G .

In order to show distinctly the passage of the outer threads to the braiding point, the position of the more important parts is shown in a perspective view Fig. 10 in the 5 moment, when the outer threads *a* meet the points of the inner bobbin carriers. In this drawing it can be distinctly seen, that the outer threads are pushed or guided below the points of the inner bobbin carriers in 10 those places, where they come into contact with the guide parts or switches *e*, whereas in those places, where the outer threads are not coming into contact with a switch or guiding part, the outer threads are slipping 15 over the point of the respective inner bobbin carrier.

What I claim is:

1. In a braiding machine, the combination with two sets of bobbins for inner and 20 outer threads revolving in opposite directions round the braiding point, of carriers supporting said bobbins, the carriers of the inner thread bobbins being pointed in the direction of their movement and provided 25 with movable points, a cam for controlling the said movable points and arranged in the path on which the inner bobbin carriers are sliding, means for revolving the bobbin supporting carriers round the braiding point, 30 and stationary non-revolving guide-pieces arranged in the meeting-places of the outer bobbin threads with the points of the afore- 35 said inner bobbin carriers for moving the outer bobbin threads to the opposite side of the points of the inner carrier points.

2. In a braiding machine, the combination with two sets of bobbins for inner and outer threads revolving in opposite directions round the braiding point, the bobbins

of the outer threads being divided into two groups moving in paths of different heights, of carriers supporting said bobbins, the carriers of the inner thread bobbins being pointed in the direction of their movement and provided with movable points, means 40 for controlling the said movable points, means for revolving the bobbin supporting carriers round the braiding point and stationary non-revolving guide-pieces, the one group of the outer threads being controlled 45 by the movable points of the inner carriers and the other group by the stationary non-revolving guide-pieces. 50

3. In a braiding machine, the combination with two groups of bobbins for inner and outer threads revolving in opposite directions round the braiding point, the bobbins of the outer threads being divided into groups, the threads of which are guided in different heights, of carriers supporting said 60 bobbins, the carriers of the inner thread bobbins being pointed in the direction of their movement and arranged in different heights, means for revolving the bobbin supporting carriers round the braiding point, 65 and stationary non-revolving guide-pieces arranged for producing two or more braids one over another connected by the inner threads. 55

In testimony, that I claim the foregoing 70 as my invention, I have signed my name in presence of two witnesses, this twenty-first day of January, 1915.

FERDINAND ROSSKOTHEN.
